UNITED STATES PATENT OFFICE.

HARRY P. NISSEN, OF OAKLAND, CALIFORNIA.

SLEEVE HOLDER.

Application filed November 22, 1928. Serial No. 149,968.

This invention relates to sleeve holders, such as disclosed in my prior application entitled Sleeve holder, Ser. No. 66,445, filed on or about the third day of November, 1925, and particularly pertains to an improved holding device adapted for use in yieldably retaining the cuff of a sleeve in any desired position on the arm.

It is the principal object of the present invention to provide an improved sleeve holding device for use in combination with snap type of cuff links, which device may be connected with the links and disposed concealed within the cuff when the cuff is in use, and will cause the cuff to yieldably grip the arm at any position thereon when the cuff is folded back on the sleeve.

In carrying out this object into practice I provide an elastic member having hooks at opposite ends for detachably connecting it to the opposite halves of the snap type of cuff links. When the cuff is in use the device is concealed within the cuff and the hooks do not interfere with the operation of the links. When the cuff is open and folded back upon itself, the elastic member is placed under tension so that the cuff will yieldably grip the arm to hold the sleeve in any desired position thereon. In this manner the cuff may be raised and retained above the elbow without rolling the sleeve, which results in wrinkling the cuff. So that it can be efficiently used the elastic member is adjustably connected with the hooks so that the distance between the hooks may be regulated to suit the size of the arm or the tension which the holder places on the cuff to retain it in position on the arm.

One form which the invention may assume is exemplified in the following description and illustrated by way of example in the accompanying drawings, in which:

Fig. 1 is a view of a portion of a shirt sleeve and arm disclosing the cuff folded back with my improved device applied to the cuff links to retain the cuff in position on the arm.

Fig. 2 is a view looking into the end of the cuff disclosing the manner in which my device is concealed within the cuff when the latter is in its normal position.

Fig. 3 is a perspective view of my improved sleeve holding device disclosing the manner in which the elastic is connected with the hooks.

Fig. 4 is a fragmentary view showing one of the hooks and one end of the elastic member being connected thereto.

Fig. 5 is a perspective view of one of the hooks.

Referring more particularly to the accompanying drawings, 10 indicates a shirt sleeve on an arm 11. The shirt sleeve is formed with a cuff 12 of conventional design, which cuff is shown as folded back upon itself in Fig. 1. It is immaterial whether or not the cuff is of double or single type. The cuff and shirt sleeve are split as at 14 and, as in standard practice, the contiguous sides of the cuff are formed with buttonholes 15 for receiving cuff links.

The present invention is particularly adapted for use in connection with the snap type of cuff links, which comprise two halves having a male and female means for frictionally connecting them. Each half of the cuff link comprises a pair of spaced collars 16 joined by a shank 17 of reduced diameter. Detachably connected to these halves of the link is a sleeve holding device 18 with which the present application is particularly concerned.

This device comprises a strip of elastic material 19 which is adjustably and detachably connected at its ends with hooks 20. These hooks are adapted to detachably engage the shanks 17 of the opposite halves of the cuff link so that they will be interposed between the inner collars 16 on the link and the inner surfaces of the ends of the cuff, as shown in Fig. 2. When the cuff is disposed as it is normally with the cuff link halves connected, the elastic portion 19 of the sleeve holding device will lie along one side of the cuff and will be concealed within the cuff, as shown in Fig. 2.

When it is desired to raise the cuff on the arm for any reason, the cuff link halves are disconnected and the cuff is folded back upon the sleeve, as disclosed in Fig. 1. This may be accomplished without disengaging the sleeve holding device 18 from the opposite halves of the cuff link. In folding the cuff over the shirt sleeve and drawing the cuff upwardly on the arm, the sleeve holding device 18 will be placed under tension so that the cuff will yieldably grip the arm. The cuffed end of the sleeve may then be drawn upwardly on the arm to any desired point, the elasticity of the portion 19 of the sleeve holder ac-

commodating the different portions of the arm encountered.

Regardless of the position of the cuff on the arm, the elastic portion 19 being placed under tension will cause the cuff to yieldably grip the arm and maintain the sleeve in the desired position. This is very desirable as it renders rolling of the sleeve unnecessary and, likewise, the hooks 20 of the sleeve hold-

10 ing device prevent the cuff link halves from becoming detached from the cuff and being lost.

In order that the sleeve holding device will fit different sizes of arms, the connection between the elastic portion 19 of the device and the hooks 20 is adjustable so that the elastic portion may be lengthened or shortened to suit conditions.

To accomplish this the hook members 20 are 20 each constructed of a single piece of material which is shaped with a hook end to engage the cuff link, and with an enlarged end to connect with the elastic strip 19. This enlarged portion is formed with two transverse 25 slots spaced slightly apart, and which are slightly greater in length than the width of the elastic strip. At the end of the hook the enlarged portion is cut away at the center to provide an opening 21 which communicates 30 with the outermost transverse slot of the hook.

To connect the elastic strip to the hook the end of the strip is inserted through the inner slot, then passed through the outermost slot. 35 This end is then rolled up tightly against the hook and the body portion of the strip is folded over the roll and passed through the slot 21. This frictionally retains the end of the elastic strip to the hook. In order to pass 40 the body portion of the elastic strip through the outermost slot, its sides are passed through the opening 21 and drawn within the outermost slot, as shown in Fig. 3. This simple means of connecting the elastic strip 19 to the hook permits the distance between the hooks to be lengthened or shortened quickly 45 and easily to suit conditions.

It will be noticed from Figs. 1 and 2 that the inner collars of the cuff link halves 16 engage

the rolls formed at the end of the elastic band- 50 member 19. Such engagement frictionally retains the hooks 20 in engagement with the cuff link halves. In other words, the hooks 20 are yieldably retained in place on the cuff link halves by means of engagement between 55 the inner collars on the cuff link halves and the rolls formed by the ends of the elastic band 19.

While I have shown the preferred form of my invention, it is to be understood that various changes may be made in its construction by those skilled in the art without departing from the spirit of the invention, as defined in the appended claims.

Having thus described my invention, what 65 I claim and desire to secure by Letters Patent is:

1. In a device of the character described, a flat member having a hook at one end adapted to releasably connect with a cuff link, the other end of said member being formed with a pair of spaced slots disposed transversely of the hooked end, the end of said member adjacent the slots being cut away to provide an opening communicating with the outermost 75 slot.

2. In a device of the character described, a flat member having a hooked end adapted to be connected with a cuff link, said member being formed with a transverse slot adjacent its opposite end and through which the end of an elastic band may be threaded, and hook portions overlying the end of the member adjacent the slot to engage the elastic band and maintain it connected with the member. 80

3. In a device of the character described, a hook member formed of a single piece of flat material, one end of said member being shaped with a hook to engage a cuff link, the other end of said member being enlarged, 90 said enlarged end being formed with two transverse slots spaced slightly apart and of a width to receive an elastic strip, the end of the enlarged portion of the member being cut away at its center to provide an opening 95 communicating with the outermost transverse slot.

HARRY P. NISSEN.
